UNITED STATES PATENT OFFICE

WILLIAM V. FASHING, OF ST. PAUL, MINNESOTA

HAIR WAVE PLACER

Application filed January 11, 1930. Serial No. 420,146.

This invention relates to hair wave placers of the type used in hair dressing, to produce waves in the outline of the hair.

The chief object of the hair wave placer is to enable the user to restore the natural symmetrical and uniform waves to the contour of the hair. This may be accomplished without the aid of a skilled hair dresser as it removes the obstacles ordinarily met by the individual unskilled in the art of hair dressing.

A further object of this invention is to provide a template that will yieldably adapt itself to fit that portion of the head to which it is applied and act as a guide against which the hair may be moulded to form a wave or curl.

It is also an object of this invention to provide a retainer to hold the waves previously formed in place while additional waves are being formed.

These and other objects and advantages of the invention will be more fully set forth in the following description made in connection with the accompanying drawings, in which like reference characters refer to the same parts throughout the different views, and in which,

Fig. 1 is a perspective view showing the hair wave placer used in forming the first wave.

Fig. 2 is an end view of the hair wave placer.

Fig. 3 is a perspective view showing the hair wave placer used in moulding the second wave.

Fig. 4 is a sectional view taken on line 4-4 Fig. 2.

Referring to the drawings the hair wave placer A is shown comprising a spring member 12 secured to a handle 10 by rivets 14. The handle 10 can also be welded to the spring member 12 or the handle 10 formed as part of the spring member 12. A resilient rubber tube 16 having corrugations 18 on its outer periphery is forced over the spring member 12 and over the lower end of the handle 10 to cover the lap of the spring member 12 and the handle 10. A suitable clip 20 having projections 22 is placed on the

end of the rubber tube 16 to close the tube and prevent the accumulation of dust and dirt in the open projecting end of the tube. After the rubber tube 16 is inserted in the clip 20 the projections 22 are forced into the rubber tube 16 holding the same in locked engagement with the clip 20.

When using the hair wave placer A, the hair B is parted at C and the comb D is used to loosen the hair and locate the first wave. The hair wave placer A is now placed on the first wave as shown in Fig. 1 and the comb D is used to complete the first wave E. After forming the first wave E the comb D is left in place and the hair wave placer A is placed in the first depression F adjacent the comb D. The comb D is now withdrawn and used to form the next succeeding wave G. This operation is repeated until all parts of the head have been treated.

The method mentioned is only one of the many ways that this hair wave placer may be used to fashion the hair.

It illustrates the use of the hair wave placer on the style of hair wave shown in the drawings. There are numerous other styles of setting the hair and the hair wave placer described will be equally useful in dressing the hair in other forms that differ for the style shown in the drawings.

In ordinary finger waving performed by the individual or by a skilled hair dresser, the finger of one hand is used to hold the hair and the wave is moulded against the finger by a comb held in the other hand. This is rather inconvenient because if the arm is brought around the back of the head, the hand will be in a cramped position.

If the arm is in front it obstructs the view in the mirror and makes the work uncertain. If the fingers are short it is impossible to form a full wave at one time. When the wave is formed by two positions of the finger it will be unsymmetrical.

This simple instrument provides a very efficient means to overcome the difficulties in the art of hair dressing and is designed for the convenient use of the individual or the skilled operator in producing a smooth and unvarying wave in the hair.

The hair wave setter will fit various sizes of heads due to the formation of the spring which is bent to fit the smaller heads and will yield to fit the larger heads when it is pressed down to hold the hair in place. The rubber tube is provided with corrugations to help prevent the hair from slipping through under the hair wave placer and the side wall of the tube acts as a gage against which the hair is formed.

In view of the foregoing description when considered in conjunction with the drawings, it will at once be apparent that I have produced a highly novel simple and extremely efficient hair wave placer that is well adapted for all the purposes heretofore designated and can be easily and cheaply constructed of materials readily available.

While the preferred form of my invention has been shown and described it is to be understood that various changes may be made in the details of construction and in the combination of the various parts, within the scope of the claims, without departing from the spirit of my invention.

I claim:

1. A hair wave placer comprising a yieldable hair retaining member and means for holding the latter in the desired position.
2. A hair wave placer comprising a handle, a resilient hair retainer and a flexible tube encasing said hair retaining member.
3. A hair wave placer, comprising a handle, a resilient member extending outward from said handle, retaining and gauging means on said resilient member.
4. A hair wave placer comprising, a formed handle, a spring extending from said handle, a flexible tube encasing said spring and having corrugations on its outer periphery and a clip secured to the open end of said tube.
5. A hair wave placer comprising a handle, a curved spring extending from said handle, a soft rubber tube encasing said spring and means to seal the open end of said tube.

WILLIAM V. FASHING.
